[57] CLAIM

The ornamental design for a photographic kiosk, as shown and described.

DESCRIPTION

FIG. 1 is a front elevational perspective view of a photographic kiosk showing my new design;

FIG. 2 is a front elevational view of the photographic kiosk of FIG. 1;

FIG. 3 is a left-side elevational view of the photographic kiosk of FIG. 1;

FIG. 4 is a right-side elevational view of the photographic kiosk of FIG. 1;

FIG. 5 is a rear elevational view of the photographic kiosk of FIG. 1;

FIG. 6 is a top plan view of the photographic kiosk of FIG. 1; and,

FIG. 7 is a front perspective view of the photographic kiosk of FIG. 1, depicting a component thereof in an extended position.

A view showing the bottom of the photographic kiosk is not provided herein since the bottom is plain and unornamented.

The opposite side of the camera pedestal of that shown in FIGS. 1, 2 and 7 forms no part of the claimed design.
